United States Patent

Des. 235,653
Patented July 1, 1975

235,653

HOUSING FOR ELECTRICAL UNIT

Anton J. Bozich, Virginia, Minn., assignor to Malton
Electric Company, Virginia, Minn.

Filed June 18, 1973, Ser. No. 370,741

Term of patent 14 years

Int. Cl. D13—03

U.S. Cl. D26—5 R

The figure shown is a view in perspective as seen from the top side and one end of a housing for electrical unit of my new design, the side and end opposite those shown are a mirror image.

The bottom, not shown, is devoid of ornamentation.

I claim:

The ornamental design for a housing for electrical unit, as shown and described.
